ELECTRIC SWITCH

Sidney Arthur Singleton, Effingham, England, assignor to Thermega Limited, London, England, a British company

Application August 6, 1945, Serial No. 609,082
In Great Britain May 3, 1944

18 Claims. (Cl. 200—138)

1

This invention relates to thermostats and switches for controlling electrical circuits and has for its object to provide a thermostat or switch having a snap action in both directions of operation so that a quick make and break of the circuit is achieved.

If a strip of springy material of curved transverse section is subjected to a force tending to bend it into a longitudinal curve it will, up to a point, resist the force, until, when said force reaches a given value, the strip will suddenly collapse. Conversely, when the strip is relieved of the bending force, it will regain its original shape, but in the initial stages of its return movement the spring will exert little force until on reaching a certain point the force increases suddenly and the spring snaps back to its original shape.

The present invention has for its object to provide a thermostat or switch having a snap action in both directions of operation by making use of the above mentioned properties of a transversely curved spring strip.

To this end an electric switch according to the invention includes in combination a blade spring fixed at one end and acted upon between its ends by an abutment, whereby the spring is flexed, said spring carrying at its free end a movable contact held against a fixed contact by a member acting laterally against a transversely curved spring strip which is held at one end and bears between its ends against a fulcrum abutment carried by the blade spring between the first mentioned abutment and the movable contact, whereby on exerting pressure on the blade spring or on the curved strip said curved strip collapses about the fulcrum thereby relieving the blade spring, thus permitting it to straighten out and bring the movable contact away from the relatively fixed contact, the curved strip suddenly snapping back to its straight condition when the pressure is relieved, whereby the blade spring is forced back to its curved condition thereby bringing the contacts together again.

In a thermostatic switch according to the invention the pressure may be exerted on the transversely curved strip by the action of a bimetallic strip acting laterally against said curved strip, the bimetallic strip having its low expansion side directed towards the blade spring so that on a

2

rise in temperature the force exerted by the bimetallic strip increases until the transversely curved strip collapses about the fulcrum, thereby relieving the blade spring and thus permitting it to straighten out and bring the moving contact away from the fixed contact.

The transversely curved strip may be fixed to the blade spring at a point between the fixed end of the blade spring and the abutment against which said blade spring bears, and the bimetallic strip may bear on the transversely curved strip at a point between the free end of the latter and the fulcrum abutment.

In a non-thermostatic switch according to the invention there may be provided an actuating member for exerting pressure on the blade spring at a point between the fulcrum abutment and the held end of the transversely curved spring. Alternatively the actuating member may exert pressure on the blade spring at a point between the fulcrum abutment and the free end of the transversely curved strip.

In order that the invention may be more completely understood two embodiments thereof will now be described by way of example with reference to the accompanying drawings in which:

Fig. 1 shows to an enlarged scale a thermostatic switch according to the invention, in longitudinal section;

Fig. 2 is a section on the line II—II in Fig. 1;
Fig. 3 is a section on the line III—III in Fig. 1;
Fig. 4 shows the transversely curved strip in plan;

Fig. 5 is an end view of the strip looking from the right of Fig. 4;

Fig. 6 shows to an enlarged scale a non-thermostatic switch in longitudinal section; and

Fig. 7 shows a modified thermostatic switch according to the invention in longitudinal section.

In the embodiment shown in Figs. 1 to 5 the thermostat comprises a rigid metal strip 1 carrying the fixed contact 2, and a bimetallic strip 3 disposed substantially parallel with the rigid strip, the two strips being spaced apart in an insulating holder 4 and the bimetallic strip 3 having its high expansion side facing away from the rigid strip 1 so that a rise in temperature will cause curvature of the bimetallic strip towards the rigid strip.

Mounted in the holder 4 between the two above

mentioned strips and adjacent to the rigid strip is a blade spring 5 carrying the movable contact 6, and mounted on the rigid strip 1 about half way along it is an abutment 7 in the form of a tension screw which bears against the blade spring 5 through an insulating plate 8, and riveted or otherwise secured to the blade spring at 9 between the tension screw 7 and the holder 4 is a strip of spring metal 10 which is curved in transverse section. (See Fig. 3.)

Carried in the free end of the bimetallic strip 3 is an adjusting screw 11 which bears against an insulating button 12, for example of porcelain, fixed to the free end of the transversely curved strip 10, and forces this strip against a fulcrum abutment 13 constituted by a dimple formed, by pressing, in the blade spring 5 between the tension screw 7 and the movable contact 6 which is carried on the free end of said blade spring.

The free end of the transversely curved strip 10 is flattened to receive the button 12, as shown at 14 in Figs. 4 and 5, the edges of the strip being turned up at an angle alongside the flattened area as shown at 15 (Fig. 5). If desired both ends of the strip 10 may be thus shaped.

This shaping of the free end or both ends of the strip 10 helps to retain the transversely curved shape of the spring and makes it more reliable with less chance of variation in strength or loss of shape at its centre due to fatigue.

Preferably the tension screw abutment 7 bears on the blade spring 5 at a point midway between the fulcrum abutment 13 and the point 9 at which the transversely curved strip 10 is attached to the blade spring 5.

The tension screw 7 and adjusting screw 11 are adjusted so that when the thermostat is at the lowest temperature to which it is normally to be subjected, the transversely curved strip 10 is straight longitudinally, while the blade spring 5, of which the normal shape is straight, is flexed to a curvature which maintains the movable contact 6 in engagement with the fixed contact 2, this flexing of the blade spring being produced by the force exerted by the adjusting screw 11, which is transmitted to the blade spring 5 through the transversely curved strip 10 and the fulcrum abutment 13.

As the temperature rises, the bimetallic strip 3 bends towards the rigid strip 1, and the adjusting screw 11 exerts a still greater force on the transversely curved strip 10, which, however, still remains straight so that the pressure on the contacts 2, 6, actually increases, the blade spring 5 distorting to permit the movement of the bimetallic strip 3.

When the temperature reaches a predetermined value the transversely curved strip 10 suddenly collapses about the fulcrum abutment 13 thereby relieving the blade spring 5 of the pressure exerted thereon through the fulcrum abutment 13, about which the transversely curved strip 10 is now kinked. Accordingly the blade spring 5 suddenly assumes its normal straight shape, and in so doing, withdraws the movable contact 6 from the fixed contact 2, thereby suddenly breaking the circuit.

As the temperature falls again, the transversely curved strip 10 tends to straighten, but, since at first it cannot exert much force, the resilience of the blade spring 5 resists this tendency and consequently, as the bimetallic strip 3 cools and moves away from the rigid strip 1, the transversely curved strip 10, still in its kinked condition, follows this movement bodily and the blade

spring 5 moves with it, the fulcrum abutment 13 remaining in engagement with the transversely curved strip 10.

Accordingly at first the contacts 2 and 6 separate still further, until, when a predetermined temperature is reached during cooling, the transversely curved strip 10 suddenly snaps back to its straight condition and forces the blade spring 5 back to its curved condition thereby bringing the contacts 2 and 6 together again.

In a modified form of thermostat according to the invention shown in Fig. 7 the rigid strip 1 of Fig. 1 may be replaced by a bimetallic strip disposed with its high expansion side facing away 15 from the other bimetallic strip 3 so that on a rise in temperature the two bimetallic strips move towards one another. With such an arrangement greater sensitivity of the thermostat is obtained because, as the temperature rises, the movement 20 of the bimetallic strip 1 carrying the contact 2 will add to the force on the transversely curved strip 10 thereby causing the latter to collapse after a smaller rise in temperature than is the case when the contact 2 is stationary as in the construction shown in Figs. 1 and 2.

In both the foregoing constructions, instead of the tension screw 7, the adjustment screw 11 may be arranged to bear on the blade spring 5 at a point between the fulcrum abutment 13 and the 30 point 9 at which the transversely curved strip 10 is attached to the blade spring 5, in which case the point at which the adjusting screw 11 bears is preferably midway between the fulcrum abutment 13 and the connection 9 between the transversely curved strip 10 and the blade spring 5. In such constructions the tension screw 7 occupies the position shown for the adjustment screw 11 in Fig. 1.

A retaining piece 16 secured to the free end 40 of the strip 1 carrying the fixed contact 2 may be bent round as at 17 to extend past the outside of the free end of the transversely curved strip 10 to act as a stop to prevent the strip from moving sufficiently far in the "cooling" direction to cause separation of the contacts should the thermostat cool down much below the lower limit of its operative temperature range.

The holder 4 for the strips and blade spring may conveniently be in the form of an insulating body, e. g. of porcelain, steatite, or an insulating plastic, having a substantially rectangular cross-section and formed with a channel 18 (Fig. 2) in one of its longitudinal faces to receive the blade spring 5 and the rigid strip 1, and with 55 a similar channel in its other longitudinal face to receive the bimetallic strip 3. The strips and the blade spring are secured in position by nuts 19 and bolts 20, the bolts passing through holes in the strips and insulating body, and being provided with insulating sleeves 21. Mica or other insulation 22 is provided under the bolt heads and nuts, and between the blade spring 5 and the strip 1 to complete the insulation.

A thermostat of the form particularly described 65 above is particularly useful for sealing into a glass tube which is evacuated or contains an inert gas, and for the purpose of holding the thermostat firmly in such a tube, spring lugs 23 may be provided at the ends of the insulating body, the 70 free ends of these lugs bearing against the side of the tube. Such lugs may be formed by the bent up ends of strips of spring metal 24 secured in the channels of the insulating body by means of the bolts 20.

The invention may also be applied to non-ther-

mostatic switches by providing, instead of the bimetallic strip, a push button by means of which pressure can be exerted on the transversely curved strip, the button being spring urged away from the transversely curved strip so that pressure on the latter is relieved when the push button is released.

Such a construction of switch is shown in Fig. 6 and comprises a rigid metal strip 1 carrying the fixed contact 2 and a blade spring 5 carrying the movable contact 6, both these elements being mounted substantially parallel to one another in an insulating holder 4, lead wires 25 being connected to the spring 5 and strip 1, which are separated by insulation 26.

Mounted on the rigid strip 1, about half way along it, is an abutment in the form of a tension screw 7 which bears against the blade spring 5 through an insulating plate 8, and, riveted or otherwise secured to the blade spring at 9, between the tension screw 7 and the holder 4, is the transversely curved spring strip 10, which bears between its ends against a fulcrum abutment 13 constituted by a dimple formed in the blade spring 5 between the first mentioned abutment 7 and the moving contact 2.

Also mounted in the insulating holder 4 on the opposite side thereof from the rigid strip 1 is a leaf spring 26 which, at its free end, carries an insulating button 27, for example of porcelain, which passes freely through a hole in the spring 26 and has a collar 27a resting against the face of the spring, the free end of the transversely curved strip 10 bearing against the other end of the button 27.

On pressing the button 27 the free end of the transversely curved strip 10 is pushed towards the rigid strip 1 until the curved strip 10 suddenly collapses about the fulcrum abutment 13, thereby relieving the blade spring 5 of the pressure exerted thereon through the fulcrum abutment 13 about which the transversely curved strip 10 is now kinked. Accordingly the blade spring suddenly assumes its normal shape and in so doing withdraws the moving contact 6 from the fixed contact 2.

On releasing the press button the transversely curved strip 10 returns to its normal position thereby permitting the blade spring 5 to close the contacts again.

Instead of mounting the push button 27 on a leaf spring 26 the button, if not too heavy and if mounted without much friction, may be guided in a fixed holder since, in such conditions the transversely curved strip will always return to its normal position on release of the push button.

The functions of the tension screw 7 and of the actuating member or push button 27 may be interchanged. In such a construction the push button 27 is carried by and will operate through the rigid strip 1 at the point of application of tension screw 7, shown in Fig. 6, while the tension screw 7 will take the place of member 27 and will be carried by a rigid member 26.

In this case the push button 27 will bear on the spring strip 5 and less movement but more pressure will be required to operate it than when the button bears upon the transversely curved spring 10, as shown in Fig. 6.

Accordingly a switch according to the invention may be constructed for low pressure high movement operation (Fig. 6 construction) or vice versa.

From the foregoing it will be observed that the

invention also includes an electric switch comprising in combination a blade spring, fixed at one end and acted upon between its ends by an abutment, whereby the spring is flexed, said spring carrying at its free end a movable contact held against a fixed contact by a transversely curved spring strip which is held at one end and bears between its ends against a fulcrum abutment carried by the blade spring between the first mentioned abutment and the moving contact, whereby on exerting pressure on the transversely curved strip by pushing an actuating member acting laterally on said curved strip either directly or through the blade spring, the transversely curved strip collapses about the fulcrum, thereby relieving the blade spring and thus permitting it to straighten out and bring the movable contact away from the fixed contact, the strip suddenly snapping back to its straight condition when pressure on the actuating member is relieved, whereby the blade spring is forced back to its curved condition thereby bringing the contacts together again.

What I claim is:

- 25 1. An electric switch including in combination a support, a blade spring fixed at one end to said support, an abutment bearing on said spring between the ends of the latter, to flex said spring, a movable contact carried at the free end of said blade spring, a fulcrum abutment carried by said blade spring between the first mentioned abutment and the movable contact, a second contact adapted to be contacted by said movable contact, a transversely curved spring strip bearing 35 between its ends on said fulcrum abutment, means holding said transversely curved spring strip at one end, and actuating means to increase the pressure between said transversely curved strip and said fulcrum abutment whereby after a predetermined pressure said curved strip collapses about said fulcrum to relieve the pressure exerted on said blade spring and to allow said blade spring to straighten out and to carry said movable contact suddenly away from said second contact.
- 40 2. A thermostatic switch including in combination a support, a blade spring fixed at one end to said support, an abutment bearing on said spring between the ends of the latter, to flex said spring, a movable contact carried at the free end of said blade spring, a fulcrum abutment carried by said blade spring between the first mentioned abutment and the movable contact, a fixed contact, a transversely curved spring strip bearing 50 between its ends on said fulcrum abutment, means holding said transversely curved spring strip at one end, and a bimetallic strip bearing laterally against said transversely curved spring strip, the bimetallic strip having its low expansion side directed towards the blade spring so that on a rise in temperature the force exerted by the bimetallic strip increases until the transversely curved strip collapses about the fulcrum, thereby relieving the blade spring and thus permitting it to straighten out and bring 55 the moving contact away from the fixed contact.
- 60 3. A switch according to claim 1 wherein the transversely curved strip is fixed to the blade spring at a point between the fixed end of the blade spring and the abutment against which said blade spring bears.
- 65 4. A thermostatic switch according to claim 2 wherein the transversely curved strip is fixed to the blade spring at a point between the fixed end of the blade spring and the abutment against which said blade spring bears.
- 70 75

5. A thermostatic switch according to claim 2 wherein the bimetallic strip bears on the transversely curved strip at a point between the free end of the latter and the fulcrum on the blade spring against which the transversely curved strip bears.

6. A thermostatic switch including in combination a support, a blade spring fixed at one end to said support; an abutment bearing on said spring between the ends of the latter, to flex said spring, a movable contact carried at the free end of said blade spring, a fulcrum abutment carried by said blade spring between the first mentioned abutment and the movable contact, a fixed contact, a transversely curved spring strip bearing between its ends on said fulcrum abutment, means holding said transversely curved spring strip at one end, and a bimetallic strip bearing laterally on the transversely curved strip at a point between the free end of the latter and the fulcrum abutment, the bimetallic strip having its low expansion side directed towards the blade spring.

7. A thermostatic switch including in combination a support, a blade spring fixed at one end to said support, a bimetallic strip having its low expansion side facing the blade spring, an abutment carried by said bimetallic strip and bearing on the blade spring between the ends of the latter to flex said spring, a movable contact carried at the free end of said blade spring, a fulcrum abutment carried by said blade spring to be disposed between the first mentioned abutment and the movable contact, a contact mounted on said bimetallic strip, a transversely curved spring strip bearing between its ends on said fulcrum abutment, means holding said transversely curved spring strip at one end, and a second bimetallic strip bearing laterally against said transversely curved spring strip, and having its low expansion side facing the first mentioned bimetallic strip, so that on a rise in temperature the two bimetallic strips bend towards one another and the force exerted on the transversely curved strip by the second mentioned bimetallic strip increases until the transversely curved strip collapses about the fulcrum, thereby relieving the blade spring and thus permitting it to straighten out and bring the movable contact away from the fixed contact, the rate of increase of said force being itself increased by the employment of the two oppositely directed bimetallic strips, and the sensitivity of the switch correspondingly increased.

8. An electric switch including in combination a support, a blade spring fixed at one end to said support, an abutment bearing on said spring between the ends of the latter to flex said spring, a movable contact carried at the free end of said blade spring, a fulcrum abutment carried by said blade spring between the first mentioned abutment and the movable contact, a fixed contact, a transversely curved spring strip bearing between its ends on said fulcrum abutment, means holding said transversely curved spring strip at one end, and an actuating member for exerting pressure on the transversely curved spring strip, said actuating member acting laterally against said curved strip at or near the free end thereof.

9. An electric switch including in combination a support, a blade spring fixed at one end to said support, a movable contact carried at the free end of said blade spring, a fulcrum abutment carried by said blade spring, a fixed con-

tact, a transversely curved spring strip bearing between its ends on said fulcrum abutment, means holding said transversely curved spring strip at one end, a member acting laterally against the transversely curved spring strip at or near the free end thereof to exert pressure on said blade spring and thereby to hold the movable contact against the fixed contact, and an actuating member acting on the blade spring at a point between the fulcrum abutment and the held end of the transversely curved strip.

10. A thermostatic switch including in combination an insulating holder, a rigid strip having one of its ends secured to one face of said holder, a fixed contact carried at the other end of said rigid strip, a bimetallic strip having one of its ends secured to the opposite face of said holder, said bimetallic strip extending parallel to said rigid strip and having its low expansion side directed towards said rigid strip, a blade spring disposed between said rigid and bimetallic strips, and having one of its ends secured to said first mentioned face of the holder, a movable contact carried by said blade spring and cooperating with said fixed contact, an abutment bearing on said blade spring between the ends of the latter, to flex said spring, a fulcrum abutment carried by said blade spring between said first mentioned abutment and the movable contact, a transversely curved spring strip secured at one end to said blade spring between said first mentioned abutment and the insulating holder, said transversely curved spring strip bearing between its ends on said fulcrum abutment, and said bimetallic strip bearing laterally against said transversely curved spring strip.

11. A switch according to claim 10 wherein the insulating holder is provided with oppositely inclined spring lugs on each of two opposite faces thereof to hold the switch firmly and centrally in a glass tube into which it is to be sealed.

12. A switch according to claim 1 wherein an end of the transversely curved spring strip is formed with a flattened area.

13. A thermostatic switch according to claim 2 wherein an end of the transversely curved spring strip is formed with a flattened area.

14. A thermostatic switch according to claim 10 wherein an end of the transversely curved spring strip is formed with a flattened area.

15. A switch according to claim 1 wherein an end of the transversely curved spring strip is formed with a flattened area and the edges of said strip alongside said flattened area are turned over at an angle to said flattened area.

16. A switch according to claim 2 wherein an end of the transversely curved spring strip is formed with a flattened area and the edges of said strip alongside said flattened area are turned over at an angle to said flattened area.

17. A switch according to claim 10 wherein an end of the transversely curved spring strip is formed with a flattened area and the edges of said strip alongside said flattened area are turned over at an angle to said flattened area.

18. In an electric switch having a fixed contact, a resilient member fixed at one end, a movable contact secured to the free end of said resilient member and adapted to contact with said fixed contact, an adjustable abutment bearing against and forming a fulcrum for said resilient member and an actuating member adapted to exert pressure on said resilient member for controlling the relative positions of said

70 fixed and movable contacts, the provision of a

fulcrum abutment provided on said resilient member intermediate its free end and said adjustable abutment and of a spring strip curved in transverse section having one end mounted on said resilient member at a point located between said adjustable abutment and the fixed end of said resilient member, said curved strip being interposed between the fulcrum abutment on said resilient member and said actuating member and having its free end contacted by 10 said actuating member.
